Attorney.

UNITED STATES PATENT OFFICE.

ANDREN WILLIAM ANDERSON, OF PITTSBURG, PENNSYLVANIA.

DEVICE FOR HANDLING SEALING-PAPER.

1,000,571.

Specification of Letters Patent. Patented Aug. 15, 1911.

Application filed June 1, 1910. Serial No. 564,506.

To all whom it may concern:

Be it known that I, ANDREN WILLIAM ANDERSON, a resident of Pittsburg, in the county of Allegheny and State of Pennsylvania, have invented a new and useful Improvement 5 in Devices for Handling Sealing-Paper; and I do hereby declare the following to be a full, clear, and exact description thereof.

10 My invention relates to devices for handling sealing paper, and has special reference to the handling of paper strips for use in the sealing of packages.

15 The object of my invention is to provide a cheap, simple and efficient device for handling sealing paper, in which gummed strips of paper used in the sealing of packages can be carried thereby, can be withdrawn therefrom, and can be moistened and cut in the 20 length desired, so as to be applied by hand to the package desired to be sealed.

25 My invention consists, generally stated, in the novel arrangement, combination and construction of parts, as hereinafter more specifically set forth and described and particularly pointed out in the claims.

30 To enable others skilled in the art to which my invention appertains to construct and use my improved device for handling sealing paper, I will describe the same more fully, referring to the accompanying drawing, in which—

35 Figure 1 is a side elevation of my improved device for handling sealing paper. Fig. 2 is a top plan view of the same. Fig. 3 is a longitudinal central section of the same.

40 Like symbols of reference herein indicate like parts in each of the figures of the drawing.

As illustrated in the drawing, 1 represents the body or box member, preferably formed of glass, and provided with the base or bottom 2, which has the paper receptacle portion 3 at the rear end thereof and the extension portion 4 at the front end of the same and extending forwardly from said receptacle. A cover 5, preferably formed of glass fits over the receptacle portion 3, and 45 is provided with a curved front portion 6 thereon for fitting against a like curved portion 2' on said portion 3. This cover 5 is held in place on the receptacle portion 3 of the member 1 by means of a downwardly extending flange 7 at the rear end of the same 50 fitting against the rear end of said portion,

and by downwardly extending lugs 8 on each side of the front portion 6 on said cover fitting within seats 8' in the extension 4 on said member.

60

Within the extension 4 is the well 9, in which is located a roller 10, preferably formed of glass, and positioned therein through the shaft portions 11 on its ends fitting within bearings 12 formed by recessed portions on the inner faces of the sides of said extension. This roller 10 is provided with shouldered portions 10' on its ends for bearing against the sides of the well 9 to reduce the friction between such 70 parts and keep the roll from binding on such sides.

65

Connected to the curved front portion 6 on the cover 5 by means of a bolt 13 is the cutting bar 14, which extends across said portion, and is provided with the knife portions 15 on each side of the same.

75

The upper face 4' of the extension 4 is inclined downwardly from the box member 1 and thus provides for an inclined paper bearing portion 16, which is adapted to form with the lower edge 6' of the curved portion 6 on the cover 5 an opening 18 between the same for the withdrawal of the paper, as hereinafter described, and such lower edge is provided with a strip of felt, as at 19, to cause tension to the paper in its withdrawal and enable pressure to be put upon such paper in its contacting with the wet roller 10, as hereinafter described. The 80 upper end of the inclined bearing portion 16 terminates in a flat portion 20, which connects with a curved portion 21 at the front end of the box member 1 and such portion 21 connects with the straight or flat portion 2' 85 of the bottom 2 of said member.

90

The box member 1 and extension 4 are caved out at the bottom of the same, as at 22, in order to lighten the device and to provide a siphonic reservoir 23 for the water 100 for the well 9, which is supplied thereto through said well, and such caved portion is closed by a plate 24 fitting in a recess 25 in the bottom 2, which is preferably formed of glass, and secured in place in said recess by 105 cementing the same or in any other suitable manner.

105

In the use of my improved device for handling sealing paper, the paper is in the form of a strip *a*, which is gummed on one 110 side as at *a'* and wound up into a roll *b*, which is placed in the box member 1 and

rests upon the straight or flat portion 2' of the bottom 2 of said member. After the roll *b* is thus in place within the box member 1 and the outer end of the paper strip *a* has 5 been drawn out over the bearing portion 16 on the extension 4, the cover 5 is placed in position over said member, which will allow such strip end to be positioned in the opening 18 between said bearing portion and the 10 front end on the curved portion 6 on said cover. In the withdrawing of the paper strip *a* from the roll *b*, the end of the same extending out of the opening 18 is grasped by the hand and drawn through said opening 15 from said roll and along the curved portion 21, flat portion 20 and over the roller 10. This operation will act to moisten the gummed side *a'* of such strip *a* by such side contacting with said roller and such roller 20 being revolved thereby within the water *c* placed within the well 9 in the extension 4. When a sufficient length of the paper strip *a* has thus been drawn from the roll *b* and moistened by the roller 10, the operator 25 throws such strip over one of the knife edges 15 on the cutting bar 14 carried by the cover 5, which will act to sever or cut such strip at the end of the moistened portion thereon, and thus leave the severed moistened portion of the desired length in the 30 hand of the operator for being pasted on the package while in a damped state, while such dry end of the strip *a* leading from the roll *b* will drop down so as to protrude from the opening 18 and will then be 35 ready for another operation of withdrawing, moistening and severing another portion of the same.

In the withdrawing of the paper strip *a* from the roll *b*, the curved portion 21 in the box member 1 will act to form a bearing surface for such roll in revolving and thereby aid the felt strip 19 in producing a pressure of the strip upon the roller 10 and 40 through the weight of the paper roll bearing on the flat portion 2' on the bottom 2 and on said curved portion.

If desired, the cover 5 can be hinged to the receptacle 3 by being formed of semi-circular shape and connected to the rear end of said receptacle by the hinge 5', as shown by dotted lines in Fig. 3, while the reservoir 23 and plate 24 can be dispensed with if desired, and it will be evident that such cover 55 and the other parts of the device can be formed of materials other than glass.

It will be evident that one or more rolls of paper can be placed within the box member and of different widths for being withdrawn therefrom, and in the case of three or more such rolls being used, two or more cutting bars can be placed on the device to sever the paper strips, while ordinary paper strips can be used in form of rolls without being 60 gummed and in place of water, mucilage or 65

other adhesive material placed in the well and reservoir for being applied by the roller to the paper.

Various other modifications and changes in the design and construction of my improved device for handling sealing paper may be resorted to without departing from the spirit of the invention, or sacrificing any of the claims.

It will thus be seen that my improved device for handling sealing paper will enable the gummed paper strip to be easily and quickly withdrawn, moistened and severed for instant application in sealing a package, and will permit the use of paper strips in sealing up some class of packages where string and cord are generally used, which will thereby save the time and eliminate the inconvenience in tying up such packages, while at the same time the package is sealed against tampering with the same, and provides for a positive wrapping of the same. The device can also be used in handling stickers, labels, etc., and advertising matter, and if desired suitable advertisements or other reading matter can be placed upon the strips before being rolled up in the rolls, or after it leaves such rolls.

What I claim as my invention and desire to secure by Letters Patent is—

1. A device for handling sealing paper strips, consisting of a box or receptacle for a roll of strips, a roller mounted in front of said receptacle for engaging with the strip as it is withdrawn from the roll in said receptacle to moisten the same for sealing, and a stationary cutter bar mounted on the front of said receptacle having the cutting edge turned toward the rear of said receptacle for severing said strip after it is moistened and withdrawn from said receptacle by the throwing of said strip over the same.

2. A device for handling sealing paper strips, consisting of a box or receptacle for carrying a roll of paper strips having a gummed surface, a roller mounted in a water well in front of said receptacle for engaging with the gummed surface of the strip as it is withdrawn from the roll to moisten said surface for sealing, and a stationary cutter bar on said receptacle having its cutting edge turned toward the rear of said receptacle for severing said strip after it is moistened and withdrawn from said receptacle.

3. A device for handling sealing paper strips, consisting of a box or receptacle having an opening in the same, said receptacle carrying a roll of strip paper, a roller mounted in front of said receptacle for engaging with the strip as it is withdrawn from the roll through said opening to moisten the same, and a soft flexible strip in said opening for engaging with said paper.

strip as it is being withdrawn through said opening.

4. A device for handling sealing paper strips, consisting of a box or receptacle having a cover thereon and adapted to form an opening with said receptacle, for carrying a roll of paper strips, a roller mounted in front of said receptacle for engaging with the strip as it is withdrawn from the roll through said opening to moisten the same for sealing, a cutter bar on the front of said cover having its cutting edge turned toward the rear of said receptacle for severing said strip after it is moistened and withdrawn from said receptacle.

5. A device for handling sealing paper strips, consisting of a box or receptacle having a cover thereon and adapted to form an

opening with said receptacle, for carrying a roll of paper strips, a roller mounted in front of said receptacle for engaging with the strip as it is withdrawn from the roll through said opening to moisten the same for sealing, and a soft flexible strip on the edge of said cover and forming part of said opening for engaging with said paper strip as it is being withdrawn through said opening.

In testimony whereof, I, the said ANDREN WILLIAM ANDERSON, have hereunto set my hand:

ANDREN WILLIAM ANDERSON.
